UNITED STATES PATENT OFFICE.

JOHN CAMPBELL, OF CLEVELAND, OHIO.

ROAD INDICATOR.

1,405,273.

Specification of Letters Patent. Patented Jan. 31, 1922.

Application filed February 1, 1921. Serial No. 441,599.

To all whom it may concern:

Be it known that I, JOHN CAMPBELL, a citizen of the United States, and a resident of Cleveland, in the county of Cuyahoga and State of Ohio, have invented a new and Improved Road Indicator, of which the following is a full, clear, and exact description.

This invention relates to improvements in road indicators, an object of the invention being to provide a road map in the form of a strip and to provide improved means for automatically exposing that part of the strip which indicates the particular road over which a vehicle is passing and which also indicates the direction to be taken when cross roads are reached.

A further object is to provide strips of this character, which are wound upon reels and to provide improved means for automatically unwinding the strips from the reels when the car is in motion.

A further object is to provide means for uncoupling the reel actuating members from the driving means, so that the strip may be adjusted for inaccuracies while the car is in motion.

A still further object is to suggest one means of conveniently mounting the indicating mechanism on the dash board of an automobile and to provide a mechanism of the character stated, which will be practical in construction and efficient in use.

With these and other objects in view, the invention consists in certain novel features of construction and combinations and arrangements of parts, to be more fully hereinafter described and pointed out in the claims.

In the accompanying drawings:

40 Figure 1 is a top plan view of my improved device;

Figure 2 is a view in longitudinal section therethrough on the line 2—2 of Figure 1;

45 Figure 3 is a view in transverse section on the line 3—3 of Figure 2;

Figure 4 is an enlarged fragmentary plan view of a portion of the film 14; and

50 Figure 5 is a detail view illustrating the mounting of the idler reel 16.

Referring in detail to the drawings, 1 represents the casing of my improved indicating mechanism. The casing may be secured in any appropriate position on a vehicle, but I have illustrated a horizontal bracket 2,

fixed to the dash board of an automobile and 55 provided with an opening 3 to accommodate the casing. The flanged edges 4 of the casing are supported by the bracket. One end wall 5 of the casing is hinged as indicated at 5', for a purpose which will hereinafter 60 appear.

A vertical bracket 6 is provided and is disposed centrally of the casing 1. The bracket 6 includes a pair of upwardly extending arms 7 and 8. Each of these arms is made 65 integral with a pair of bearing sleeves, such as 9.

Shafts 10 and 11 are mounted to turn in the bearing sleeves 9 on the arm 7 and spindles 12 are carried by the sleeves on the 70 arm 8.

13 represents a cartridge reel, upon which is wound a roll of film 14. This cartridge reel is mounted on one end to turn freely on the lower spindle 12 and is provided with 75 a conical recess in its other end, which receives a cone shaped member such as 15, projecting inwardly from the end wall 5 of the casing.

Mounted to turn freely on the upper spindle 12 and on a similar cone shaped member is an idler reel 16, provided adjacent each end with an annular series of teeth 17 adapted to engage in perforations 18 along the 80 edges of the film 14.

85 A driven reel 19 mounted to turn with the shaft 10, is similar to the reel 16, being provided with pins 20, which positively engage the film to unwind it from the cartridge reel and deliver it on to a receiving reel 21, 90 mounted to turn with the shaft 11. The reel 21 frictionally engages the shaft 11 and normally turns therewith, but is adapted to slip on the shaft to relieve the strain on the film incidental to the varying speeds of the 95 peripheries of the two reels 19 and 21.

The shafts 10 and 11 are compelled to turn simultaneously in the same direction by virtue of a gear wheel 22 fixed to the shaft 10 and a gear wheel 23 fixed to the shaft 11, 100 both of which mesh with an idler gear wheel 24 mounted on the arm 7. The gear wheel 23 is slightly smaller than the gear wheel 22, so that the reel 21 is driven at a greater speed than the reel 19, as above suggested.

105 The film 14 has displayed thereon a road map such as 25, and a line 26 upon the map indicates the course to be taken. If desired

- the map may also have displayed along one edge a scale of miles, such as 27, to indicate the ground covered. It will of course be understood that the driven reel is geared to 5 drive the film in direct ratio to the speed of the car, so that the portion of a road over which the car is travelling is always exposed through a transparent portion 28 in the top of the casing. The transparent portion 28, 10 preferably comprises a sheet of glass secured in any suitable manner within a hinged section 29 of the top of the casing. The section 29 is hinged as indicated at 30 for a purpose to be hereinafter noted.
- 15 It will be evident that numerous means might be resorted to for imparting motion to the shaft 10. For the purpose of illustration I have shown one practical and efficient means of accomplishing this object.
- 20 As before noted, the film reels occupy one end of the casing between the brackets 6 and the hinged wall 5. In the other end of the casing, my improved actuating mechanism is mounted. A driving shaft 31 extends 25 through the end wall of the casing and has its end journaled in an upstanding bracket 32. The drive shaft may either be connected to the speedometer, or to the front axle of a vehicle.
- 30 The driving shaft 31 through a suitable speed reducing worm gear, such as 33, transmits motion to a vertical counter shaft 34, turnable in bearings, such as 35, within the casing. The counter shaft 34 through an 35 other reducing gear, preferably a worm, as indicated at 36, transmits motion to the driven shaft 10. The shaft 10 is formed in two sections, which are compelled to turn together by a clutch such as 37. One member 38 of the clutch is mounted to slide on one section of the shaft 10, as indicated at 39. A spring held clutch controlling lever 40 is pivoted to the upper end of the bracket 32 and includes a fork 41, engageable around 45 the clutch member 38 to positively slide the same in either direction. An expansion spring 42 tends to maintain the clutch member 38 in operative position to impart motion to the reel 19. The lever 40 is of the 50 angular shape illustrated and its upper end terminates in a downwardly presented hook 43.
- 55 It may become necessary to adjust a film for slight inaccuracies which occur through wear on the transmission gear and with this in view, I provide a beveled gear 43', around the shaft 10 between the gear wheel 22 and the clutch.
- 60 A hollow post 44 is integral with one edge of the casing section 29 and a vertical shaft 45 is mounted to turn freely in the post. A finger receiving disc such as 46, on the end of the shaft 45 facilitates manual operation of the same. The shaft is normally maintained in elevated position by a spring held
- dog 47 engageable in annular grooves 48 in the shaft. A bevelled gear wheel 49 is fixed to the lower end of the shaft 45 and a flange 50 of considerably greater diameter than the gear wheel 49 is fixed to the shaft above the 70 gear wheel. The flange 50 is engageable with the lever 40 to swing the clutch member 38 out of operative position when the shaft 45 is moved downwardly.
- 75 It is desirable that the lever 40 be held in the position illustrated in dotted lines in Figure 2, so that the film may be adjusted by moving the bevelled gear 49 into operative engagement with the gear wheel 43'. With this end in view, an angular spring held member, such as 51, is pivoted at its intermediate portion in the upper end of the casing. The member 51 includes at one end an upwardly presented hook 52, engageable with the hook 43. A slidable plate 53 mounted on the top of the casing is engageable with the other end of the member 51, which extends outwardly through an opening 54 in the upper corner of the casing. By moving the plate 53 to positively engage the free end of the member 51, the hook 52 is moved into engagement with the hook 43, to hold the clutch member 38 out of the path of the bevelled gear 49. The gear 49 may then be moved into engagement with the gear 43', 90 upon the shaft 10 to manually adjust the film.
- 95 Any approved means of manually operating the plate 53, such for instance, as the handle 55, may be employed.
- 100 The hinged side wall 5 permits the introduction of the film into the casing, and the hinged section 29 permits ready access to all of the parts for the purpose of repair.
- 105 It will be apparent that other means might be utilized for mounting the reels and that various changes and alterations might be made in the general form and arrangement of the parts described without departing from the invention and hence I do not limit myself to the precise details set forth, but shall consider myself at liberty to make such slight changes and alterations, as fairly fall within the spirit and scope of the appended claims.
- 110 An indicator finger 56 secured to one edge of the transparent portion 28 indicates the exact location of the car on the road.
- 115 I claim:
1. A device of the character described including a casing, a vertical bracket disposed centrally of the casing, a film carrying cartridge reel mounted to turn freely between the bracket and the one end wall of the casing, a driven reel mounted in the casing, 120 means on the driven reel positively engageable with a film to unwind the film from the cartridge reel, a film receiving reel and means normally causing the receiving reel to turn simultaneously with the driven reel, 125 130

and means for relieving tension on the film between the receiving reel and the driven reel.

2. A device of the character described including a casing, a vertical bracket disposed centrally of the casing, a film carrying cartridge reel mounted to turn freely between the bracket and the one end wall of the casing, a driven reel mounted in the casing, means on the driven reel positively engageable with a film to unwind the film from the cartridge reel, a film receiving reel and means normally causing the receiving reel to turn simultaneously with the driven reel, said means comprising a pair of gear wheels fixed to turn with the driven reel and the film receiving reel and an idler gear wheel meshing with both of said first mentioned gear wheels.

20 3. A device of the character described comprising a casing, a film carrying cartridge reel mounted to turn freely in the casing, a driven reel in the casing, means on the driven reel positively engaging the film to unwind it from the cartridge reel, a driven shaft operatively connected to the driven reel, means for driving the driven shaft, said means comprising a drive shaft mounted in the casing, a counter shaft, a reducing gear connecting the drive shaft and counter shaft, and means operatively connecting the counter shaft and the driven reel.

4. A device of the character described comprising a casing, a film carrying cartridge reel mounted to turn freely in the casing, a driven reel in the casing, means on the driven reel positively engaging the film to unwind it from the cartridge reel, a driven shaft operatively connected to the driven reel, means for driving the driven shaft, said means comprising a drive shaft mounted in the casing, a counter shaft, a reducing gear connecting the drive shaft and counter shaft, and means operatively connecting the counter shaft and the driven reel, and a reducing gear transmitting motion from the counter shaft to the driven shaft.

5. A device of the character described comprising a casing, a film carrying car-

tridge reel mounted to turn freely in the casing, a driven reel in the casing, means on the driven reel positively engaging the film to unwind it from the cartridge reel, a driven shaft operatively connected to the driven reel, means for driving the driven shaft, 55 said means comprising a drive shaft mounted in the casing, a counter shaft, a reducing gear connecting the drive shaft and counter shaft, and means operatively connecting the counter shaft and the driven reel, and a reducing gear transmitting motion from the counter shaft to the driven shaft, said driven shaft comprising two sections, a clutch normally compelling both sections to turn together, means for manually operating the 60 driven shaft and means whereby one clutch member is automatically moved out of operative position, when the manually operable means is moved into engagement with the driven shaft.

6. In a device of the character described, a casing, a flexible strip of material having a map displayed thereon, said casing including a transparent portion adapted to display said map, means for driving said map, a 70 clutch associated with said means, a pivoted clutch fork controlling the clutch, means for manually adjusting the strip, a pivoted spring held hooked arm engageable with the clutch fork to hold out the clutch during 75 manual adjustment of the strip, means for locking said fork in inoperative position.

7. In a device of the character described, a casing, a flexible strip of material having a map displayed thereon, said casing including a transparent portion adapted to display said map, means for driving said map, a clutch associated with said means, a pivoted clutch fork controlling the clutch, means for manually adjusting the strip, a 80 pivoted spring held hooked arm engageable with the clutch fork to hold out the clutch during manual adjustment of the strip, means for locking said fork in inoperative 85 position, said means including a sliding locking member mounted on the casing and engageable with one end of the hooked arm.

JOHN CAMPBELL.
